UNITED STATES PATENT OFFICE.

HIRAM A. CARTER, OF PAWTUCKET, RHODE ISLAND.

SEPARABLE BUTTON.

SPECIFICATION forming part of Letters Patent No. 227,730, dated May 18, 1880.

Application filed February 27, 1880.

To all whom it may concern:

Be it known that I, HIRAM A. CARTER, of Pawtucket, in the county of Providence and State of Rhode Island, have invented a new and useful Improvement in Separable Buttons; and I hereby declare that the following is a full, clear, and exact description of the same, reference being had to the accompanying drawings, forming part of this specification.

This invention has reference to that kind of separable buttons in which two push-bars are used to release the shoe of the button, so that the button cannot be separated by accidental pressure on one of the push-bars.

The invention consists in the peculiar construction of the spring and push-bars, made in one piece of stamped metal, and in the parts forming the button, as will be more fully set forth hereinafter.

Figure 1 is a sectional view of my improved separable button. Fig. 2 is an end view of the button proper, and Fig. 3 is a perspective view of the several parts forming the button and shoe.

In the drawings, A is the disk of the button, provided with the rim b, which has the slots c c, through which the pusher-bars project, cut into the same.

B is the spring-latch and pusher-bars, stamped in one piece out of sheet metal. It consists of the bent spring d, the catches e e, and the push-bars f f. The whole is stamped from hard-rolled sheet metal in one piece, and, as it is not subjected to heat, will retain its springiness.

E is the cap or cover within which the spring-latch and pusher-bars are secured. It consists of the rimmed disk g and tubular stem h, one end of which is closed, and is provided with 40 the slits i i, in which the pusher-bars and catches move.

F is the shoe, provided with the tubular stem k, the lower part of which is expanded and suddenly contracted so as to form the lip l, 45 which, passing over the catches e e, contracts the same and the spring d, and, entering under the catches, secures the shoe to the button.

When the spring and pushers B are inserted into the cap E, the cap is secured to the front 50 button, A, by drawing the rim b over the cap g, and the whole is thereby firmly held together without solder and without the use of heat, the spring retains its original temper, and a strong durable button is produced at 55 the least possible cost without skilled labor.

Having thus described my invention, I claim as new and desire to secure by Letters Patent—

In a separable button, the combination, with 60 the disk A, provided with the rim b, having the notches c c, of the spring d, catches e e, and pushers f f, and the cap E, provided with the rimmed disk g, the closed tubular stem h, and the slits i i, secured to the disk A, as described, and the shoe F, the whole constructed 65 substantially as described.

HIRAM A. CARTER.
